UNITED STATES PATENT OFFICE.

HENRY J. JACOBS, OF BUFFALO, NEW YORK, ASSIGNOR TO THE BUFFALO LOUNGE COMPANY, OF SAME PLACE.

RECLINING-CHAIR.

SPECIFICATION forming part of Letters Patent No. 664,322, dated December 18, 1900.

Application filed August 18, 1900. Serial No. 27,244. (No model.)

To all whom it may concern:

Be it known that I, HENRY J. JACOBS, a citizen of the United States, residing at Buffalo, in the county of Erie and State of New York, have invented new and useful Improvements in Reclining-Chairs, of which the following is a specification.

This invention relates to that class of reclining-chairs in which the adjustable back is held in a more or less inclined position by a bail or yoke extending across the rear side of the back and having forwardly-extending arms which interlock with toothed bars arranged on the chair-body.

15 The objects of my invention are to simplify the construction of the devices which hold the adjustable back in position and to so arrange the same as to render the chair slightly in appearance and so as not to require a departure from the conventional form of such chairs.

In the accompanying drawings, Figure 1 is a side elevation of a reclining-chair provided with my improved adjusting device, the upholstery being omitted. Fig. 2 is a rear elevation of the chair. Fig. 3 is a perspective view of the bail or yoke. Fig. 4 is a similar view of one of the toothed brackets.

Like letters of reference refer to like parts in the several figures.

25 A is the stationary body of the chair, which has the usual front posts A', rear posts A'', and the arm-rests A³, secured to the upper ends of said posts.

35 B is the adjustable back, which is hinged at its lower end to the rear portion of the chair-body adjacent to the seat, as shown at b.

C is an approximately U-shaped yoke or bail which is pivoted to the back B, so that 40 its free arms or side bars c are capable of swinging vertically. The cross-bar c' of this yoke extends across the rear side of the chair-back, about in line with the arm-rests A³, and is pivoted to the upright side members of the back by clips c² or other suitable means. The yoke-arms are provided at their free ends with lips or projections c³, which are arranged 45 at right angles to the arms and engage with toothed upright bars d, secured to the rear posts A² of the chair-body. The teeth of each of these bars face forwardly and are all ar-

ranged in a vertical row, one below another, and their upper sides are inclined and their lower sides abrupt, similar to ratchet-teeth. Each of the ratchet-bars d is preferably cast 55 in one piece with a bracket D, having a vertical slot d', in the rear wall of which the ratchet-teeth are formed. The locking-lips c³ of the yoke C pass through the slots of the brackets D and are adapted to slide vertically in said slots and interlock with a set of the ratchet-teeth for holding the adjustable chair-back in a more or less inclined position. The arms of the yoke may be provided with indented or outwardly-bulged portions 60 e, which form convenient handles for manipulating the yoke.

When the angular ends of the yoke are located in the upper portion of the brackets D and it is desired to move the chair-back to a 70 more upright position, the occupant of the chair can readily adjust the back by simply pulling the same forwardly, the free angular ends of the yoke riding automatically over the inclined upper sides of the ratchet-teeth 75 until the chair-back arrives at the desired angle, when the ends of the yoke interlock with the adjacent teeth of the brackets by the pressure of the occupant against the chair-back. When the free ends of the yoke 80 are located at the lower end of the brackets and it is desired to adjust the chair-back to a more reclining position, the occupant pulls the back forwardly sufficient to release the front ends of the yoke from the teeth of the 85 brackets and raises the yoke-arms until the back reaches the desired angle, when by leaning against the back the angular ends of the yoke interlock with the toothed bars.

In case the occupant should accidentally 90 release the chair-back in adjusting it rearwardly the angular ends of the yoke, owing to the vertical arrangement of all of the ratchet-teeth d, will automatically engage with the next or adjacent set of teeth, thereby 95 preventing the back from falling rearwardly to the limit of its movement and rendering its adjustment more convenient.

By arranging the upright toothed bars on the rear posts of the chair-body, as shown, 100 and employing a vertically-swinging yoke in connection therewith these parts require no

change in the construction of the chair which detracts from its sightliness, but permit the same to be made according to approved conventional forms. This construction and arrangement of the adjusting devices also dispenses with the use of separate catches for locking the front ends of the yoke-arms in position, thereby reducing the cost of the chair and facilitating the adjustment of the back.

I claim as my invention—

The combination with a chair-body having rear posts which extend above the chair-seat, and an adjustable back hinged at its lower end to the chair-body, of upright toothed bars secured to said rear posts and facing

forwardly, and each having all of its teeth arranged vertically, one below another, said teeth having forwardly-inclined upper sides and abrupt lower sides, and a vertically-swinging yoke pivoted to the chair-back and having arms which extend forwardly to said toothed bars and terminate in lips or angular portions which engage with said toothed bars, substantially as set forth.

Witness my hand this 10th day of August, 1900.

HENRY J. JACOBS.
